UNITED STATES PATENT OFFICE.

CLARENCE E. SMITH, OF PEORIA, ILLINOIS.

RAZOR-STROPPING MACHINE.

Application filed November 4, 1921. Serial No. 512,829.

To all whom it may concern:

Be it known that I, CLARENCE E. SMITH, a citizen of the United States, residing at Peoria, in the county of Peoria and State of Illinois, have invented new and useful Improvements in Razor-Stropping Machines; and I do hereby declare that the following is a full, clear, and exact description of the invention, which will enable others skilled in the art to which it appertains to make and use the same.

This invention has reference to razor stropping machines, pertaining more particularly to a stropping device adapted to be held wholly in the hands of the user.

An object of the invention is to provide in a stropping device a body portion carrying a blade holder, and two reciprocating parts movable with respect to one another in opposite directions and with respect to the body portion, and adapted in their movement to cause the blade being sharpened to be alternately and automatically reversed in position and moved against stropping members carried by said parts.

Another object is to provide a stropping device wherein a body portion carrying a blade holder supports two members adapted to reciprocate in opposite directions and each carrying a stropping portion, one of the members being geared to the other whereby in a movement of one of them a like movement must result in the other but in an opposite direction, the movement of one of such members acting to rock the blade to be sharpened and carrying its edge against the two stropping portions, and to shift the blade whereby to realize the desired diagonal stropping action.

Another object is to provide a stropping device that will not be likely to get out of order, that can be easily operated, and will quickly sharpen a blade due to the movement imparted to the latter.

In the appended drawing forming part hereof,

Figure 1 is a side elevation of my stropping machine whose parts are partially distended.

Figure 2 is a plan of one side thereof.

Figure 3 is an end elevation.

Figure 4 is a transverse section on line 4-4, Figure 2.

Figure 5 is a longitudinal section.

Figure 5^a shows in perspective a friction spring.

Figure 6 shows a portion of a blade carrier in perspective.

Figure 7 shows a blade holding structure also in perspective, and

Figure 8 is a longitudinal sectional elevation of parts of the holder shown in Figure 7.

The stropping device includes a body portion comprises side members 1 having at opposite edges enlargements 2, Figure 3, said sides being connected by end members 3 forming a frame. Also connecting the said side members at one side of the frame is a part 4, Figures 4 and 5.

Engaging the enlargement 2 at one side of the said frame is a portion 5, constituting a slide, whose edges are turned inwardly to enclose said enlargements, as most clearly shown in Figures 3 and 4. Secured upon one of the turned edges is a toothed rack 6 whose teeth mesh with those of a pinion 7 rotatable upon a stud 8 extending from one of the side members 1 of the described body portion. The opposite ends of the slide 5 are each provided with a flange 9 extending substantially at right angles to the plane thereof in the direction of the body portion and a stropping portion 10 such as leather, for example, is stretched from one to the other and secured at its ends thereto.

Engaging one of the enlargements 2 opposite those engaged by the slide 5 just described is the flanged edge 11 of a frame 12, the opposite edge of said frame terminating inside the opposite enlargement 2 or in spaced relation thereto. This frame likewise has end flanges 13 corresponding to the flanges 9 of the side 5 and a stropping portion 14 is stretched between and is secured at its ends thereto.

15 is a channel portion engaging the remaining free enlargement 2 and slidably therealong. It has a depending arm 15' adapted for rocking a blade holder to be described.

16 is a plate corresponding to the slide 5 whose edges are turned inwardly to embrace the flange 11 of the frame 12 and the channel portion 15 as clearly shown in Figure 3. Said plate is secured to the frame 12 by bolts 17, for example, which extend through both near their ends, Figure 2. The said plate 16 and frame 12 constitute a second slide which includes a toothed rack 16' engaging the pinion 7.

Depending from the said plate 16 is an

abutment 18 carrying a spring 19 adapted to frictionally engage the said channel portion for a purpose to be explained.

Mounted upon the part 4 connecting the sides 1 of the body portion, Figures 5 and 7, is a blade carrier comprising end plates 20 and a bottom connecting portion 21, the latter being pivoted at 22 to said part 4 so as to swing in a plane parallel to that in which the body lies. Extending between and secured to the end plates 20 are members 24 which are spaced from one another in a direction perpendicular to the plane of the said body portion a distance substantially equal to the distance between the stropping portions 10, 14, Figure 5, the said portions, in their travel to be described, moving upon them.

Each of the said end plates 20 has a circular opening therein and one of them receives a disc 25 outside of which, Figure 7, is a plate 26, secured thereto and having an extension 27 provided with a pin 28 which engages in a slot 29 of the arm 15' depending from the channel portion 15.

In the opening of the other end plate 20 is a disc made up of two half portions 30, 31, Figure 8, spaced from one another to leave a slot 32 there-between. The portions are secured to a plate 33 having a slot 34 therethrough of a width sufficient to admit a razor blade.

Also, the end plate itself has a slot 35 for the same purpose with which said slots 32 and 34 can be brought in register. The blade supporting device consists of two spaced strips 36, attached at one of their ends to the disc 25 at one end of the carrier and at their other ends to the half disc 30 at one side of the slots 34, 35, Figure 8, and of a carrier consisting of a strip 37 of a width no greater than the diameter of the disc made up of the halves 30, 31 so that the whole can rock within the openings in said end plates 20. One end of the strip 37 is bent at right angles to its plane into a head 38, a shank 39 being formed between the head and the strip by reducing the width thereof, allowing it to extend between the strips 36; the strip 37 lying at one side of the strips 36 and the head 38 at the other, thus maintaining the named portions in assembled relation.

The said strip 37 is provided with studs 40 or any other means to receive and hold the razor blade. The strips 36 and strip 37 are a sufficient distance apart to admit the razor blade which is wafer thin, said blade being placed upon the said strip 37 after pulling the latter outward, Figure 7. When pushed back between the end plates 20 the blade is securely mounted and may rock with the carrying parts without chance of becoming displaced.

It is observed that since the plates 26

and 33 carrying these discs are outside the end plates 20, and that the strips 36 connect said discs, the rocking structure thus created cannot in any way leave the end plates 20.

The depending arm 15' of the channel portion 15 when given a longitudinal movement through the shifting in both directions of said channel portion imparts a vibratory movement to the plate 26 through the pin 28 by which the razor blade is rocked first in one direction and then in the other, carrying its edges against the stropping portions so that each side of the blade at both edges can be stropped, it being observed that the members 24 form a backing for those portions of the stropping portion with which the blade edges have contact.

In addition to rocking the blade in the manner described the frame made up of the end plates 20, said members 24 and the portion 21, is made to swing parallel to the stropping portion upon the pivot 22 in and due to the movement imparted to the said plate 26, such movement being limited by pins or stops 41 extending from the sides 1 of the body portion. These stops are spaced from one another, one lying at each side of the said frame.

To operate the device the slides 5 and 16 are grasped in the hands and shifted in opposite directions. Due to the fact that the pinion 7 is carried on the body portion and the toothed racks 6, 16' engage it, the slides move in unison to the same extent and maintain a certain relation to the body portion at all times.

The spring 19 described has constant frictional engagement with the channel portion 15 so that in each shifting movement of the said plate 16 the portion 15 is carried with it as far as the pins 41 will permit the blade carrier to swing, the plate 16 continuing its movement with respect to the said portion. That is to say the initial movement of the plate 16 shifts the portion 15, rocking the blade to one limit of its movement (contact of blade edge with the stropping portions), followed by shifting the blade carrying structure on its pivot 22 to place the blade edge in a diagonal position with respect to the stropping portion, the plate continuing its movement, in the direction imparted, with respect to said portion 15.

A reversal of movement of the slides reverses the blade position both as to the contact with the stropping portions and the diagonal position with respect thereto.

The device is simple in its appointments, easily operated, the operation is positive, the parts cannot readily get out of order, the diagonal stropping is realized in a most perfect manner, and the device takes up but

small space in a traveler's kit and cannot be damaged in any way since the stropping portions are fully enclosed and protected when the ends of slides and body portions 5 are brought flush with one another in the closed position as shown by dotted lines in Figure 1.

The pinion and toothed racks positively prevent movement of either slide except in 10 direct relation to one another to the end that there can be no danger of shifting either of the stropping portions in a direction to carry it against the blade in a direction that might injure it. In other words the travel 15 of the stropping portions is and must be always away from the cutting edge of the blade. Preferably the flanged edges of the slides are knurled to furnish a grip for the hands as an aid in operating the device. 20 The compactness, rigidity and strength of the device is notable and appealing. While I may make slight changes in the construction and arrangements of the parts of the device they will be such as will fairly fall 25 within the invention and the appended claims.

I claim:

1. A razor stropping device including in its construction a support, a frame mounted therein, a rocking blade-holder journaled in the frame, a slide at each of two opposite sides of the support adapted for simultaneous reciprocating movement in opposite directions, a stropping member carried by each 30 slide, a series of teeth on each slide, an idler-pinion mounted on the support in permanent engagement with both series of teeth, an arm extending from the rocking blade-holder, and an arm extending from one of the slides having operative engagement with the first named arm adapted to rock the blade-holder in the reciprocations of the slide. 40

2. A razor stropping machine including in its construction a support, a frame pivoted on the same and free to swing, a rocking blade-holder mounted in the frame, a slide at each of two opposite sides of the support adapted for simultaneous reciprocating movement in opposite directions, a stropping member carried by each slide, a series of teeth on each slide, an idler-pinion mounted on the support in permanent engagement with both series of teeth, an arm extending 45 from the rocking blade-holder, and an arm extending from one of the slides having operative engagement with the first named arm adapted to rock the blade-holder in the reciprocations of said slide. 55

3. A razor stropping device including in its construction a support, a frame pivoted on the same and free to swing, means to limit the swinging movement of the frame, a blade-holder mounted in the frame, a slide 60 at each of two opposite sides of the support

adapted for simultaneous reciprocating movement in opposite directions, a stropping member carried by each slide, a series of teeth on each slide, an idler-pinion mounted on the support in permanent engagement 70 with the teeth of both slides, an arm extending from the blade-holder, and an arm extending from one of the slides having operative engagement with the first named arm adapted to rock the blade-holder in the reciprocating movements of said slide. 75

4. A razor stropping device including in its construction a support, a frame pivotally mounted therein adapted to swing parallel to the plane thereof, a blade-holder mounted in said frame adapted to oscillate, slides adapted for reciprocating motion mounted one at each side of the support in permanent slidable relation, a stropping portion carried by each slide, and means operated by one of the slides for engaging and imparting movement to both the frame and the blade-holder. 80 85

5. A razor stropping device including in its construction a support having guideways 90 on two opposite sides thereof, a slide at each side engaging the guideways, a stropping portion carried by each slide facing one another within the support, a frame mounted within the support between the stropping portions, a blade-holder mounted in the frame between the stropping portions adapted to oscillate, means to oscillate said holder and to swing the frame carrying said holder comprising an arm on the latter and an arm engaging it moved by one of the slides, and spaced portions on the support to receive the frame against them for limiting the swing of such frame. 95 100

6. A razor stropping device including in its construction a support, a slide mounted thereon adapted to reciprocate, a stropping portion carried by it, a frame pivoted on the support adapted to swing in a plane parallel to the plane of the said stropping portion, a blade-holder mounted in the frame adapted to oscillate including a pair of spaced portions lying parallel to one another, a member engaging the portions and overlying them, said portions and the member adapted to receive and hold a razor blade between them, an arm secured to the spaced portions, and a member carried by the slide engaging said arm. 110 115

7. A razor stropping device including in its construction a support, a frame pivoted at its middle within the same, a blade-holder mounted in the frame adapted to rock, there being an opening in the frame and in the support through which to insert and withdraw a blade, a slide having permanent engagement with the support at each side including a stropping portion and adapted to reciprocate simultaneously in opposite directions, means independent of the blade-holder 125 130

adapted to engage the reciprocating portions for causing them to move in unison, an arm attached to the blade-holder, and an arm extending from one of the slides and operatively connected to said arm of the blade-holder adapted to rock said blade-holder and to swing the frame on its pivot.

8. In a razor stropping device, a support, a frame pivoted thereon, a blade-holder mounted in the frame adapted to rock, a slide mounted permanently at each of two opposite sides of the support adapted to reciprocate in opposite directions in unison,

a secondary slide frictionally engaging one of the first named slides, an arm extending from the blade-holder, and an arm extending from the said secondary slide adapted to engage that of said blade-holder and to rock the latter and the frame in the movements of the first named slides. 15 20

In testimony whereof I affix my signature in presence of two witnesses.

CLARENCE E. SMITH.
